United States Patent Office

Des. 182,955
Patented June 3, 1958

182,955

DENTAL CHAIR SEAT

Norman A. Hana, San Francisco, Calif., assignor to Hek Manufacturing Company, San Francisco, Calif., a partnership of California

Application April 29, 1957, Serial No. 45,941

Term of patent 14 years

(Cl. D15—3)

FIG. 1

FIG. 2

Fig. 1 is a side elevational view of a dental chair showing my new design for the seat thereof; and

Fig. 2 is a top plan view showing a dental chair embodying the new seat design of the present invention.

The dominant features of the design reside in the portion shown in full lines.

I claim:

The ornamental design for a dental chair seat, substantially as shown and described.
